UNITED STATES PATENT OFFICE.

DAVID HONEYWOOD, OF BATTERSEA, ENGLAND.

CRUSHING AND GRINDING MILL.

No. 921,248.

Specification of Letters Patent.

Patented May 11, 1909.

Application filed December 11, 1908. Serial No. 466,978.

To all whom it may concern:

Be it known that I, DAVID HONEYWOOD, a subject of the King of Great Britain, residing at No. 120^A Queens road, Battersea, in 5 the county of Surrey, England, have invented a new and useful Improvement in Crushing and Grinding Mills, of which the following is a specification.

This invention relates to improvements in 10 apparatus for crushing or grinding metallic ore, rock, cement and the like of the type in which the stamps are mounted on piston rods, the pistons of which are reciprocated by pressure fluid supplied by compressors or 15 pumps and in which the stamps are revolved or the mortars are revolved while the stamping is proceeding.

The object of the invention is to provide 20 more simple and efficient means whereby the crushing is obtained in a shorter time than has been possible with apparatus heretofore in use, it being possible for the improved machine to work at very high speeds.

This invention consists in providing the 25 compression cylinder and stamp cylinder with such an arrangement of ports, valves and passages as to effect the holding of the stamp head in suspension or raised during part of the period of compression in the compression cylinder and to then allow the cumulative pressure above the stamp piston to give a strong and swift impulse to the stamp piston, owing to a sudden release of the pressure below the stamp piston. This action is 30 principally brought about according to these improvements by providing the compression cylinder with an inlet port a little below the middle of its length adapted to be uncovered and covered by the piston, (the cylinder being also provided if desired with a relief valve at or near one or both its ends as common practice may show to be necessary or advantageous). The lower end of the stamp cylinder is connected to the compression cylinder by two ports or passages formed more or less in the form of a Y, one port or passage opening into the compression cylinder at about the level of the inlet port referred to, and the other port or passage opening into valved chamber in the lower end of the compression cylinder. In connection with these primary improvements certain accessory devices working on known principles may be provided as for instance a 45 valve for relieving the compression in any particular stamp of a battery for the purpose

of putting such stamp out of action; also a gear for rotating or oscillating the stamps or the mortars. The piston of the stamp chamber may be provided at its upper end with an annular valved chamber. And in order that this invention may be more readily understood, it will be described with reference to the accompanying drawings illustrating its application to a small battery of vertically 60 acting stamps, in which drawings:—

Figure 1 is a view partly in front elevation and partly in section. Fig. 2 is a plan of the cylinders. Fig. 3 is a section on the line III—III Fig. 1, and Fig. 4 is a transverse sectional elevation.

As shown on the drawings the compression cylinders *a* are mounted on the top of a suitable frame or entablature *b*, in the lower part of which is carried in suitable bearings 75 *c* the crank shaft *d* by which latter through connecting rods *e*, the parallel rods *f* and cross-heads *g*, the pistons *h* are actuated. The parallel rods are guided as shown in holes in lugs on the upper and lower cylinder 80 covers. The crank-shaft *d* may be driven by pulleys and belting or otherwise from a steam engine, electric motor, or other suitable means.

The stamp motors comprise pistons *k* 85 reciprocally mounted in cylinders *i* which are preferably arranged in front of the compression cylinders *a*. The pistons *k* have piston rods *l* to the lower ends of which are fixed the stamps *m* for effecting the crushing 90 or grinding operation in the mortar boxes *n*.

The means for providing for the admission of air or other fluid to the compression cylinders and for the admission to and the exhaust of such pressure fluid from the stamp cylinders is as follows:—The compression cylinders are each provided preferably a little below the middle of the length thereof with a port *o* for the admission and escape of air, which port is open to the atmosphere 100 when the piston approaches its lowest and highest positions. The lower end of the compression cylinder *a* is provided with a chamber *p* or false bottom, the bottom proper of the cylinder, which is perforated 105 at *q*, forming the top side of this chamber, the perforations being closed automatically by pressure from below by means of a disk valve *r* of leather or other suitable material. This chamber *p* is in direct communication 110 with the bottom of the motor cylinder *i* by means of a port passage or conduits *s*, so

that when air is compressed in the lower end of the compression cylinder *a* by the descent of the piston *h*, the said air will pass through the perforations *q* into the chamber *p* and thence by the port *s* to the lower end of the stamp cylinder *i* beneath the motor piston *k* thus tending to raise the latter preparatory to the working stroke for effecting the blow. An exhaust port and passage or conduit *t* is also provided from the lower end of the stamp cylinder to near the middle of the compression cylinder *a* and in connection with the aforesaid passage *s* to the lower end of the compression cylinder and these two passages approximately resemble the letter *Y*, the object being to permit the lower part of the stamp cylinder *i* to be entirely free from pressure preparatory to the downward or working stroke. The port *t* is preferably connected to the compression cylinder *a* a little below the middle of the length that is to say it is about opposite to the inlet port *o*. The discharge passage *u* leads from the top of the compression cylinder *a* to near the top of the stamp cylinder *i*, sufficient space being allowed to leave an air cushion between the cylinder cover and the top of the stamp piston *k*. The top of the stamp piston *k* is fashioned so as to provide an annular chamber *v* access to which is had by ports *w* normally covered by a suitable valve. In the example shown this valve consists of a disk of leather *x*, the object being to allow of the admission of compressed air into the annular chamber to start the piston *k* when the top of the latter is above the port of the passage *u*, but to allow of the action of the compressed air on the full area of the piston when the latter has descended a short distance.

To destroy any vacuum that may be produced on the under side of the compression piston *h*, a spring relief valve *z* or other suitable means are provided to admit air to the cylinder *a* and the upper end of the cylinder may also be provided with a cock *1*. The compression cylinder *a* is also suitably provided with one or more small ports *2* which are covered by an external flap valve *3*. The said port *2* is for the purpose of permitting of the escape of a certain amount of air during the latter portion of the down stroke of the compression piston *h* and consequently during the corresponding portion of the up stroke of the stamp piston *k* and it further provides for the release of some of the pressure fluid from the compression cylinder during the up stroke of the piston therein.

To increase the efficiency of the stamps they are provided with suitable gear for imparting an intermittent or continuous rotary or oscillatory motion, or alternatively the mortar boxes *n* may be adapted to rotate or oscillate or both the stamps and the mortar boxes may have rotary or similar motion

imparted thereto the object being to have both a rotary and a reciprocating motion during the stamping so that in addition to the crushing action there is also a grinding action taking place.

A convenient arrangement for imparting rotary motion to the stamps is shown on the drawings and it comprises a shaft *4* mounted in bearings *20* and parallel to the crank shaft *d*, which by a pair of miter wheels *5* communicates motion to a shaft *6* also mounted in bearings and carrying a miter wheel *7* which meshes with another miter wheel *8* on the shaft *4*. Mounted on this shaft *4* is a bevel wheel *9* gearing with a bevel wheel *10* which has made in one therewith or fixed thereto a spur wheel *11*. The bevel wheel *10* and spur wheel *11* are provided with a square hole or the like through which freely passes the stamp piston rod, correspondingly shaped, so that as the wheels revolve they communicate revolving motion to the stamp piston rod while however leaving it free to reciprocate. The bearings for the wheels *10* and *11* are mounted on a cross piece *12* which also supports bearings for the spur wheels *13* and *14*. These latter are also provided with square holes or the like and the stamp piston rods are similarly fashioned so that they are guided in the spur wheels as well as caused to revolve therewith. The spur wheel *11* gears with an intermediate pinion *15* and the spur wheel *13* gears with a pinion *16* which again gears with the spur wheel *14* so that rotary motion is communicated to all three stamp piston rods *l* while allowing of the free reciprocation of the latter. If desired chain and sprocket wheels or other suitable means may be employed instead of bevel gear to drive the shaft *4*.

The lower ends of the stamp rods *l* may if desired be provided with means for permitting of their revolution or oscillation while the upper ends and the pistons *k* merely reciprocate. The spur wheels *11*, *13* and *14* are preferably provided with suitable clutch gear (not shown) so that they may be disengaged when required, for example when renewal of a stamp head is required.

In a battery of stamps it may be desirable to mount the stamps in what might be termed a graduated series of mortar boxes so that the material fed from the hopper into the first box (the middle one in the example shown) is crushed or ground to a degree of fineness and finds its way thence by gravity aided by the centrifugal force due to the rotary motion of the crushing heads through the discharge passages *17*, *17* into the two side boxes to be still further pulverized or into a second box and from thence into a third box or into several boxes in rotation until the desired degree of fineness is attained. The stamp heads *m* may be graduated, that is to say, they may be of

varying diameters and provided with flat, serrated, concave or other form of base or sides or both as may be found most convenient.

- 5 In the case of dry crushing, where dust is prevalent, it is most desirable to incase the whole of the moving parts (with the exception of the stamp heads *m* and the parts of the stamp rods which must be exposed) and 10 in Fig. 4 of the drawings a shield 18 is shown to incase the crank shaft connecting rods *e*, lower cross heads *g* and the lower ends of the parallel rods *f*. The lower ends of the stamp rods may also be provided with bearings or 15 guides in, for instance, the cross-member 12, or there may be another guide such as that marked 12^a, in addition to the guidance afforded by the holes in the bosses of the spur wheels such as 11, 13 and 14.
- 20 In a battery of stamps it may be necessary to renew one or more stamp heads *m* and, to avoid putting the whole battery out of action, provision is made whereby one or more of the stamps may be disconnected or prefer- 25 ably held in its raised position, while such renewal is being effected. For this purpose the upper cover of each compression cylinder *a* is provided with a cock or as shown with a cock such as marked 1 in the side of the cyl- 30 inder near the top which enables the dis- charge from the upper part of the cylinder to be ejected into the atmosphere or otherwise instead of through the discharge port *u* to the stamp cylinder *i*. The port to the lower 35 end of the latter from the compression cylinder must of course be closed to effect this, a convenient means for doing the same con- sisting in providing the port *t* with a valve or cock, the plug of which is marked 19, and 40 shown in Fig. 4. Consequently it will be possible for the compression piston *h* to recipro- cipate without effecting a reciprocation of the stamp piston *k* and as there will only be fluid pressure on the lower side of the piston 45 *k*, it follows that the latter will be kept in its raised position which is most convenient for changing the stamp *m* while the recipro- cation of the compression piston will be con- tinuous. As fresh air is constantly being 50 drawn in and passed from the compression cylinder to the stamp cylinder and back to the compression cylinder whence it is dis- charged again, it follows that the apparatus 55 is kept cool and a water jacket is not re- quired.

The action of the apparatus is as follows:— Assuming the compression piston *h* to be, as shown, at the bottom of the stroke, then the stamp piston *k* will be at the top of its cyl- 60 inder *i* with a small air cushion between the top cover of the cylinder and the top of the piston *k* while the lower end of the cylinder is filled with compressed air. Air is ad- mitted into the compression cylinder *a* by 65 the inlet port *o* and is compressed during the

upward stroke of the piston *h* after the latter has closed the port *o* and subsequently the port 2 in its ascent. The air compressed is discharged through the passage *u* into the annular space *v* near the top of the stamp 70 piston, and escapes therefrom through the ports *w* and past the valve *x* into the top of the stamp cylinder *i*. As soon as the piston *k* has been forced down a short distance, the upper end of the said piston is clear of the 75 port of the passage *u* and the rest of the charge of compressed air acts on the upper surface of the valve *x* on the top of the stamp piston *k* to effect the impact or blow. The discharge or exhaust of compressed air from 80 below the stamp piston *k* is not permitted until the compression piston *h* has traveled suf- ficiently far to uncover the exhaust port *t*, with the result that the pressure on the stamp piston *k* is relieved and a high effective degree of 85 compression is obtained on the upper side of the stamp piston *k*, so that the stamp *m* gives a blow of considerable force. The compression piston *h* now descends. In so doing it closes the inlet port *o* and the exhaust port *t* 90 and uncovers the port 2. The air below the said piston is compressed forcing the valve *r* in the chamber *p* away from its seat so that the air passes from thence through the port or passage *s* to the lower end of the stamp 95 cylinder *i* and consequently raises the stamp piston *k* therein preparatory to the next working stroke or blow, while it will be readily understood that any accumulation of pressure on the upper side of the stamp pis- 100 ton *k* is released when there is a clear way from the passage *u* to the port 2, the valve on which opens outwardly as stated.

What I claim and desire to secure by Letters Patent of the United States is:—

1. In a stamp, a fluid compressor cylinder having a fluid supply, a motor cylinder, a piston therein, ducts connecting said cylinders, a piston in the compressor cylinder, means adapted to prevent the escape of ex- haust from one side of the motor piston while the compression is taking place on the other side, the motor piston being mean- 110 while remote from the impact end of its stroke and means to permit the escape of the fluid at a predetermined point of the stroke of the compressor piston.

2. In a stamp, a fluid compressor cylinder, a motor cylinder, a piston therein, ducts connecting said cylinders, a piston in the 120 compressor cylinder, means adapted to lock compressed fluid in the motor cylinder to oppose the working stroke of said motor pis- ton and means controlled by said compressor piston to permit the escape of said fluid at a predetermined period.

3. A stamp comprising in combination, a fluid compressor cylinder, a piston therein, means for reciprocating said piston, a motor cylinder, a piston therein, a stamp head con- 130

nected with the latter, ducts connecting said cylinders, a back pressure valve coöperating with one of said ducts, said motor piston controlling another of said ducts and adapted 5 to open the latter at a predetermined instant in the cycle of the piston.

4. A stamp comprising in combination a motor cylinder, a piston therein, a stamp head, a rod connecting said piston with said 10 head, means adapted to alternately supply fluid on opposite sides of said piston and to lock the fluid upon one side of the piston during a portion of the time it is being supplied to the opposite side.

15 5. A stamp comprising in combination a fluid compressor cylinder having a port therein, a piston in the cylinder, driving means for said piston, a motor cylinder, a piston therein, a stamp head operatively 20 connected with said piston, connective ducts between corresponding ends of said cylinders, a back pressure valve in connection with one of said ducts, a third duct communicating between that end of said motor 25 cylinder adjacent said stamp head and the compressor cylinder intermediate its ends said third duct and port being so disposed that the compressor piston can rise above both but can only descend beneath said port.

30 6. A stamp comprising in combination a fluid compressor cylinder having a port therein, a piston in the cylinder, driving means for said piston, a motor cylinder, a piston therein, an annular chamber in said 35 piston, passages in said piston communicating between said chamber and the space behind said piston, a back pressure valve covering the outer ends of said passages, a stamp head operatively connected with said 40 piston, a connective duct between one end of said compressor cylinder and a point intermediate the ends but near one end of said motor cylinder, a second connective duct between the other ends of said cylinders, a back pressure valve in said second 45 duct, a third duct communicating between that end of said motor cylinder adjacent said stamp head and said compressor cylinder intermediate its ends, said compressor piston, third duct and port being so disposed that said compressor piston can rise above both but can only descend beneath said port, substantially as and for the purpose set forth.

55 7. A stamp comprising a fluid compressor cylinder having an inlet port, a piston in the cylinder, driving means for the piston, a motor cylinder, a piston therein, a stamp head operatively connected with the latter, ducts 60 connecting the corresponding ends of said cylinders, a back pressure valve coöperating with one of said ducts, a duct communicating with the compressor cylinder through a port intermediate the ends of the latter and with the motor cylinder at the end nearest the

stamp head, a valve in the last named duct, a valved port in the upper end of the compressor cylinder communicating with the atmosphere, said compressor piston adapted to uncover the inlet port and the intermediate port at the end of its up stroke and to uncover the inlet port at the end of its down stroke. 70

8. A stamp comprising in combination, a plurality of motor cylinders, a piston in each 75 of said cylinders, a plurality of stamp heads, operative connections between corresponding pistons and stamp heads, a mortar for each stamp head, a connective duct between two of said mortars a compressor cylinder 80 for each motor cylinder, supply ducts adapted to alternately supply fluid from the compressor cylinders to opposite sides of the motor pistons, a piston in each compressor cylinder adapted to lock fluid upon one side of 85 the corresponding motor pistons while said fluid is being supplied to the opposite side, and means controlled by the compressor pistons to unlock the fluid at predetermined instant. 90

9. A stamp comprising in combination a fluid compressor cylinder having an inlet port therein, a compressor piston in the cylinder, driving means for said piston, a motor cylinder, a motor piston in said cylinder, a stamp head operatively connected with said piston, revolving means in sliding but non-rotative connection with said stamp heads, operative connection between said driving means and said revolving means, connective 95 ducts between corresponding ends of said cylinders, a back pressure valve in connection with one of said ducts, a third duct communicating between that end of said motor cylinder adjacent said stamp head and said 100 compressor cylinder intermediate its ends, said compressor piston, third duct, and port being so disposed that said compressor piston can rise above both but can only descend beneath said port, substantially as and for the purpose set forth. 105

10. A stamp comprising in combination a fluid compressor cylinder having a port therein, a compressor piston in the cylinder, driving means for said piston, a motor cylinder, a motor piston in said cylinder, a stamp head operatively connected with said piston, a pinion, sliding but non-rotative connection between said pinion and stamp head, bevel 110 gearing operatively connecting said driving means and pinion, connective ducts between corresponding ends of said cylinders, a back pressure valve in connection with one of said ducts, a third duct communicating between that end of said motor cylinder adjacent 115 said stamp head and said compressor cylinder intermediate its ends, said compressor piston, third duct and port being so disposed that said compressor piston can rise above both but can only descend beneath said port, substantially as and for the purpose set forth. 120

125

substantially as and for the purpose set forth.

11. A stamp comprising in combination a compressor cylinder, a reciprocatory compressor piston in said cylinder having an open ended cavity therein, driving means for said piston, a motor cylinder, a reciprocating motor piston and piston rod in said cylinder, a stamp head connected with said rod, a connective duct between adjacent ends of said cylinders, a non-return valve in connection with said duct opening only toward said motor cylinder, a connective duct between the opposite end of said compressor cylinder and a point a little removed from the opposite end of said motor cylinder, a chamber in said motor cylinder adapted to register with the last named duct, ports communicating between said chamber and the portion of said cylinder between said duct and the adjacent end of said cylinder, a back pressure valve covering said ports and opening only toward said cylinder portion, a third connective duct between that end of said motor

cylinder first referred to and said compressor cylinder intermediate the ends of the latter, a port in said compressor cylinder approximately in line with the opening of said third duct, a non-return suction valve adjacent one end of said compressor cylinder, an escape valve intermediate said port and the other end of said compressor cylinder, said open ended cavity in said compressor piston in alinement with said port when said piston reaches that end of its stroke in which position said third duct remains closed by the piston, said piston being adapted to uncover said port and the opening of said third duct when at the opposite end of its stroke, substantially as set forth. 40

In testimony whereof I have signed my name to this specification in the presence of two subscribing witnesses.

DAVID HONEYWOOD.
